METHOD OF MAKING TUBULAR
WORKPIECESStevenson Findlater, McKeesport, Pa., assignor to
National Tube Company, a corporation of New
Jersey

Application November 17, 1937, Serial No. 175,157

1 Claim. (Cl. 88—62)

According to current practice, seamless pipes and tubes are usually made by piercing a billet, reducing the wall thickness and elongating the pierced billet by two or more passes through a plug or high-mill and, then reeling the workpiece. The plug or high-mill consists of a pair of grooved rolls with a mandrel plug positioned therebetween so that the wall thickness of the pierced shell is reduced by the compression to 5 which the wall is subjected, by the rolls pressing the wall against the mandrel plug. The workpiece, after being passed through the high-mill, is turned 90 degrees on its longitudinal axis and passed again through the high-mill to 10 obtain a reduction around its entire circumference.

Since it is necessary under practical operating conditions to provide the grooved rolls of the high-mill with an outwardly flared portion at the 20 edges thereof in order to prevent the formation of a fin or flash (due to the fact that all of the metal displaced will not move longitudinally of the tube) it has heretofore been the conventional practice to provide a flared portion of 30 degrees 25 or more on both edges of the groove. This flared portion has a customary radius of approximately double that of the arc comprising the balance of the roll groove contour. Thus 60 degrees or more on each side of the tube which passes 30 through the high-mill is not reduced, or is only partially reduced, after its first pass through the high-mill, which necessitates its being turned 90 degrees on its longitudinal axis and passed again through the high-mill to roll the unrolled portion.

While this procedure has been more or less satisfactory for the production of relatively heavy or thick-walled tubes it has not proven satisfactory for light-walled tubes where the drop in temperature of the workpieces during the 35 interval of preparation for the second pass is sufficiently great to cause a considerable variation in the unit strength of the metal at different points around the perimeter of the workpiece. The characteristic shape of the tears which have 40 been observed in the tube walls indicates that the variation in displacement and in peripheral speed around the groove has imposed definite and severe stresses in the tube wall during the rolling operation. When the stresses act on a workpiece which, on account of the above mentioned, 45 temperature conditions, varies in unit strength throughout the cross-section, the combination is often sufficient to cause failure with consequent cobbling. The nature of this phenomenon is 50 evident when it is realized that in the conven-

tional groove contour approximately 60 degrees on each side of the tube section remains unrolled and partially unrolled after the tube has been given its first pass.

It is obvious that, in the elongation made in 5 the second pass, the previously worked portion of the tube section then lying in the flared area of the groove obtains the majority of its elongation from forces from within the wall of the workpiece. To relieve this condition, which is 10 particularly disadvantageous in rolling light-walled tubes, I have designed a contour for the high-mill roll grooves which, in combination with certain other elements, permits the securing of 15 the desired reduction and elongation in a single pass through the high-mill. Thus, the flaring in the grooves used for rolling light-walled tubes is reduced to the minimum consistent with good operation, it being understood that if the flare is reduced too much a fin will be formed on two 20 sides of the shell which cannot be removed by the subsequent reeling operation. However, the tendency to form a fin can be overcome while still reducing the flare to a considerable extent by maintaining the workpiece as it is pierced at a 25 diameter not more than $\frac{1}{8}$ inch larger than the groove diameter and, where possible, the shell diameter should be the same or slightly less than the groove diameter. Thus, a portion of 30 the reduction and elongation is due to the shell being pulled or expanded over the plug by the rolls, the rolls thereby having the triple function of pulling the shell over the plug, confining the periphery of the shell and also reducing the wall of the shell by their regular function as rolls. It 35 is to be noted that the position of the plug relative to the center line of the high-mill rolls should be such that any wall reduction made by the rolls is made on the outside diameter of the shell. In other words, the surface of the plug contacted 40 by the billet in and slightly in advance of the working zone should be cylindrical, or at least not smaller, at the point of initial rolling contact, in order to reduce the friction between the shell and the plug. Furthermore, the friction 45 or "bite" afforded by the roll groove surface should be identical for the two high-mill rolls. To accomplish this the analysis, hardness and structure of the rolls should be identical.

It is accordingly among the objects of the 50 present invention to elongate tubular workpieces in a single pass through a high-mill.

The foregoing and other objects will be apparent after referring to the drawing in which:

Figure 1 is a fragmentary elevation of a pair of 55

high-mill rolls which have been constructed in accordance with the teachings of the invention.

Figure 2 is a view similar to Figure 1 but disclosing rolls of smaller size, although shown in larger scale.

Referring more particularly to the drawing the latter A designates a pair of high-mill rolls having complementary grooves. In the specific example shown the grooves B have a diameter of $9\frac{3}{4}$ inches but it will be understood that this diameter will vary in accordance with the size of the finished tubular article desired. The edge portions X of the grooves are flared or have an augmented radius over an arc ranging from 10 degrees for larger sizes of tubular workpieces up to 20 degrees for the smaller diameters. In conventional high-mill practice this arc is somewhat larger, it being customarily about 30 degrees for the diameter shown in Figure 2 and the radius thereof about twice the radius of the groove. I have found that the radius of this flared portion can be reduced to about $1\frac{1}{4}$ to $1\frac{3}{4}$ of the radius of the groove B. In the preferred embodiment illustrated this radius is $1\frac{1}{2}$ that of the radius of the groove B, without producing any undesirable fin or overfill which cannot be removed in the reeler and still produce the desired elongation in one pass of the workpiece therethrough. The extreme edges of the grooves B are rounded off as shown at Y in the drawing to eliminate any tendency for the rolls A to form a fin on the workpiece.

A more uniform displacement of the metal in the wall of the workpiece is secured around its entire circumference and a greater percentage of the entire wall is supported between two confining surfaces than was heretofore considered feasible. Additional frictional effort is imparted

to the workpiece by the high surface speed portion of the roll groove, thus reducing the magnitude of the forces required from within the wall of the workpiece to effect elongation in the partially rolled section lying in the flared area of the groove. Since the elongation can be made in a single pass lighter-walled tubular workpieces can be produced than was heretofore possible and the total elongation can be made under favorable temperature conditions which do not exist where a time interval elapses between the first and second pass of the conventional high-mill reduction. Furthermore, the elongating in a single pass through the high-mill permits of additional temperature in the workpiece at the 15 reelers, thereby permitting more effective removal of surface irregularities.

While I have shown and described several specific embodiments of my invention it will be understood that I do not wish to be limited exactly thereto, since various modifications may be made without departing from the scope of the invention, as defined by the following claim.

I claim:

A method of making tubular workpieces which includes supporting a tube over an interiorly disposed mandrel, compressing said tube at diametrically opposite points over arcuate areas of 170 degrees to 175 degrees to thereby cause a slight overfill but no fin at the portions on the exterior of the tube not under compression, said last-named step being conducted without producing any substantial change in the outside diameter of the tube, and subsequently removing surface irregularities and said slight overfills by 35 a reeling operation.

STEVENSON FINDLATER.
